UNITED STATES PATENT OFFICE

2,362,495

JACK

Gilbert L. Mayberry, Newark, N. J.

Application May 6, 1943, Serial No. 485,839

1 Claim. (Cl. 254—113)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a jack for use in aligning, positioning, and to enable the tight fitting of objects in relatively confined spaces.

The device hereinafter described has particular application and utility in the packing and storing of ammunition canisters, and will be so described, but it is to be understood that it is not to be so limited.

In the storing of ammunition canisters into freight cars certain rules and requirements of the Interstate Commerce Commission make it mandatory that wooden partitions be set up after a fixed number of canisters have been loaded into the car. In this manner, within each freight car there will be several compartments each containing a certain number of canisters, with each compartment being separated from the compartment next adjoining by a wooden partitioning board.

In the past this has been accomplished by placing the partitioning board against the end row of the canisters and by utilizing a crow bar or similar wedging device to force the board firmly against the canisters to a tight fit position. The board is then nailed to the floor of the freight car and another section of canisters is set up and a similar practice followed. It is obvious that by the practice outlined above the labors of two operators are required, one to keep the partitioning board in position with the crow bar, while the other nails the board to the floor of the car.

By the utilization of the device forming my invention, I provided means whereby a single operator alone can perform each of the operations indicated above.

The invention can best be understood from the following description to be read in view of the accompanying drawing in which:

Fig. 1 is a side view of the preferred embodiment of the invention; and

Fig. 2 is a view of the device in its applicable use in a box car.

Fig. 3 is an end view of the device.

Referring to the drawing, I indicated one arm of the Jack which tapers at one end to form a handle 2. The other end of arm 1 is linked to

a base board 3 by means of a pivot pin 4. At the distal end of base 3 there is secured thereto a pair of staking pins 5 adapted to be staked into the floor of the box car. Linked to the arm 1 is another arm 6 having an enlarged head 7. It is obvious that movement of the arm 1 about its pivot pin 4 will control the movement of arm 6.

The operation of the device herein described can be set forth as follows: Canisters 8 are stacked upon the floor 9 of the box car in the manner shown. When a determinate amount of canisters is stacked a partitioning board 10 having an extended base portion 11 is pressed against the canisters while at the same time base 3 of the device is staked into the floor utilizing the staking pins 5. The handle 1 is first drawn back and then pushed in the direction of the canisters causing arm 6 to press firmly against the partition board 10. Continual exerted pressure upon the handle 1 will force the canisters into as tight a fit as necessary. The extended base portion 11 of the partition board can then be nailed to the floor of the box car. After this is completed the arm 1 is drawn away from the canisters and arm 6 is thereby released and the apparatus is then ready for re-use.

While the device herein set forth has been described in its application to the floor of a box car, it is obvious that it can be similarly adapted for use on the side walls of the car to serve the same purposes herein before described.

It will be noted that the base 3 of the jack is elongated sufficiently so that the operator may place his foot thereon between the lever pivot 1 and the spurs during the operation of the jack.

What is claimed as new is:

A jack comprising an elongated base, a lever pivotally mounted in a recess adjacent the forward end of the base, said base being provided on its underside and solely at the end opposite the lever and remote from said lever, with rearwardly projecting spurs for entering the base-support to stabilize the base, and a presser arm pivotally attached to the lever adjacent the base, said arm extending in advance of the base for engagement with an object to be positioned, said base being sufficiently elongated so that the operator's foot may be placed thereon between said lever pivot and said spurs during the operation of the jack.

GILBERT L. MAYBERRY.
